UNITED STATES PATENT OFFICE.

OLAUS B. JACOBS, OF ROLAND, IOWA.

GATE.

SPECIFICATION forming part of Letters Patent No. 703,423, dated July 1, 1902.

Application filed May 8, 1901. Serial No. 59,260. (No model.)

To all whom it may concern:

Be it known that I, OLAUS B. JACOBS, a citizen of the United States, residing at Roland, in the county of Story and State of Iowa, have 5 invented a new and useful Gate, of which the following is a specification.

This invention relates to gates, and particularly to that class of gates described in my copending application, filed May 8, 1901, Serial No. 59,259. In said application there is described and claimed a gate which can and will be opened by one class of stock, but will be locked in closed position against the passage of another class. The construction set 15 forth in the specification of said application is primarily intended to pass swine, but bar sheep in one direction, but will permit of the passage of both in the other direction. Under many conditions this is an excellent construction, in that should a sheep from any cause get into the adjoining field or pasture it may readily pass back to the flock through the gates. Under other conditions, however, said structure is very disadvantageous. For 20 instance, swine could not be permitted to run through adjoining fields having different breeds of sheep, for the reason that while the sheep in one field could not pass to the other those in the adjoining field could readily pass 25 through the gate to the first, and thus the gate would be practically useless.

The object of this invention is to provide a construction which will overcome this objection by permitting one class of stock to pass 30 freely in either direction, but will be locked against movement in either direction to another class, and in the following specification there is described a construction that can be thus operated by swine, but is inoperative to 35 sheep. This construction is also illustrated in the accompanying drawings, wherein—

Figure 1 is a perspective view of the gate. Fig. 2 is a view of the same in elevation, portions of the keeper-plates being broken away. 40 Fig. 3 is a vertical sectional view illustrating the manner in which it is unlocked.

Similar numerals of reference designate corresponding parts in all the figures of the drawings.

50 In carrying out the invention a pair of spaced standards 10 are arranged in the fence to form a passage-way, in which a swinging

gate 11 is mounted. This gate comprises bars 12, connected by stringers 13, thus forming a panel which is arranged to close the 55 passage-way. The panel is pivoted at its upper end to the standards 10, suitable spacing-blocks 14 being secured to the latter, and pivot-pins 15 passing through the same and engaging the side bars 12. The lower ends 60 of the side bars 12 project some distance below the lowest stringer 13, and to their projecting ends is pivotally secured the locking device, (designated as a whole by 16.) This locking device 16 consists of a transverse 65 holding-bar 17, fastened to upright blocks 18, which are pivoted to the lower ends of the side bars 12 of the gate-panel by means of eyebolts 19, through the eyes of which pass staple-bolts 20, secured to the said side bars. 70 The eyebolts 19 also serve to fasten the holding-bar 17 to the blocks 18. The ends of the holding-bar 17 project beyond the side edges of the gate-panel and normally rest in notches 21, located in the upper edges of upright 75 keeper-plates 22, secured transversely across the lower portions of the posts or standards 10. The ends of these notches form stop-shoulders 23, against which the projecting ends of the holding-bar 17 abut, and thus 80 limit the swinging movement of the gate in both directions. Connecting the depending ends of the blocks 18 is the operating rail or plate 24, which hangs transversely across the gateway below the lowest stringer 13 of the 85 panel.

In normal position the gate-panel hangs in a vertical position between the posts, with the ends of the holding-bar resting in the notches of the keeper-plates. The gate is 90 thus locked against opening, and should a sheep attempt to force a passage in either direction the holding-bar will abut against the shoulders 23 of the keeper-plates. On the other hand, assuming that a pig attempts to 95 pass through its natural instinct impels it to attempt to root under. If therefore it is on the side shown in Fig. 3, it will press against the operating-board, thus swinging the locking device and raising the holding-bar out of 100 the notches of the keeper-plates. Upon further forward movement the gate will be opened sufficiently to permit the pig to pass under, after which it will swing back to locked

position. If the pig is on the opposite side of the fence, in like manner it will attempt to root under; but the operating-bar is so located that it cannot be reached from this side. The animal's head instead contacts with the under side of the holding-bar 17 and lifts it up and out of operative position as the gate swings forward, thus releasing it and permitting the passage of the pig. In order to prevent the pigs rooting under the gate, a platform or flooring 25 may be laid between the posts and for a sufficient distance on each side of the same. By this construction, therefore, a very simple gate is provided which 15 may be operated in either direction by one class of animals, but is an absolute bar to other classes, and thus, as shown, pigs can have a range through adjoining fields, while sheep and other animals are kept within their respective confines. The entire structure is furthermore exceedingly inexpensive in construction and the parts are such that there is little chance of their becoming derauged. From the foregoing it is thought that the 25 construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what 30 I claim as new, and desire to secure by Letters Patent, is—

1. The combination with a supporting structure having a gateway, of a vertically-swinging gate pivoted in the gateway and leaving 40 an open space therein, locking means movably mounted upon the gate for holding it against opening, and operating means for the lock located in the open space of the gateway and movable transversely of the gate.
- 45 2. The combination with a fence having a gateway, of a gate pivoted in the gateway and leaving an open space therein, said gate having a free swinging movement in both directions, locking means for holding the gate 50 against opening in either direction, and operating means for the lock, said means being located in the open space of the gateway.
- 55 3. The combination with a fence having a gateway, of a vertically-swinging gate pivoted at its upper end in the gateway and having its lower edge spaced from the ground or floor leaving an open space, locking means movably mounted upon the gate to hold it against opening, and an operating device for the lock 60 located in the open space below the gate and movable transversely thereof.

4. The combination with a fence having a gateway, of a vertically-swinging gate pivoted at its upper end in the gateway and having its lower edge spaced from the ground or floor leaving an open space, locking means movably mounted upon the gate to hold it against opening, and an operating device for the lock located in the open space below the gate and movable transversely thereof. 70

5. The combination with a swinging gate, of a lock pivoted to the gate to hold the same against opening, and operating means suspended from the lock and depending below the lower edge of the gate. 75

6. The combination with spaced supporting-standards, of a vertically-swinging gate pivoted to the standards, a transverse locking-bar pivoted to the gate to engage means located upon the standards to hold the gate against opening, and an operating-plate secured to the locking-bar and depending beneath and movable transversely of the gate. 80

7. The combination with spaced supporting-standards, of a vertically-swinging gate pivoted at its upper end to the upper ends of the standards, keeper-plates secured to the standards, and having notches in their upper edges, a transverse locking-bar pivoted to the gate and normally engaging in the notches of 90 the keeper-plates, and an operating-plate secured to the locking-bar and depending beneath and movable transversely of the gate. 95

8. The combination with a vertically-swinging gate, of a lock movably mounted upon the 100 gate, and operating means for the lock carried by and depending below the lower edge of the gate, said operating means being movable transversely of the gate.

9. The combination with a swinging gate, of spaced stops located adjacent to the gate, a lock carried by the gate and arranged to have a movable engagement between the stops to permit of a limited movement of the gate, and operating means for the lock. 105

10. The combination with a swinging gate suspended from its upper end, of locking means for the gate mounted upon the lower end thereof, and a keeper arranged contiguous to the lower end of the gate and having 110 spaced stops between which a portion of the lock movably engages to permit of a limited movement of the gate without unlocking the same.

In testimony that I claim the foregoing as 115 my own I have hereto affixed my signature in the presence of two witnesses.

OLAUS B. JACOBS.
